UNITED STATES PATENT OFFICE.

ANDREW C. FARNSWORTH, OF CHICAGO, ILLINOIS, ASSIGNOR TO THE
IMPERIAL BALL BEARING AXLE COMPANY, OF SAME PLACE.

DESIGN FOR A VEHICLE-HUB CAP.

SPECIFICATION forming part of Design No. 24,489, dated July 16, 1895.

Application filed February 21, 1895, Serial No. 539,288. Term of patent 14 years.

To all whom it may concern:

Be it known that I, ANDREW C. FARNSWORTH, a citizen of the United States, residing at Chicago, in the county of Cook and State of Illinois, have invented and produced a new and original Design for Vehicle-Hub Caps or Bands, of which the following, in connection with the accompanying drawings, is a full, clear, and exact specification.

In the said drawings, Figure 1 is a perspective view of a hub-cap, showing my design; and Fig. 2 is a longitudinal sectional view thereof.

The leading features of my design consist of the representation of an angular nut A, having the circular portion a' and the plate or end piece B, through which said nut A and portion a' apparently protrude. The plate B and the cylindrical portion C, in the end of which said plate is arranged, apparently form or constitute the end of a hub, the plate B being concaved and its edges gradually rounded off to meet the edge c of the cylindrical portion C, so that such edge c will appear like the edge of the ring or ferrule of an ordinary hub. The inner end of the cylindrical por-

tion C, or that end which adjoins the hub D, represented in dotted lines, is provided with a finishing rib or ridge E.

The body portion of the imitation nut A is 30 square and faced with a circular surface a , while between such body portion and the face of the plate B appears the circular flange a' of the nut, such flange being formed in relief on the face of the plate B, and its face and 35 the sides of the imitation nut being stippled or pebbled to form a contrast with the finished face of the plate B and the finished surface a of the nut. The outer end of the imitation nut is substantially flush or in a plane 40 with the edge c of the cylindrical portion C, as shown in Fig. 2.

Having thus described my design, what I claim as new, and desire to secure by Letters Patent, is—

The design for vehicle hub caps or bands substantially as herein described and shown.

A. C. FARNSWORTH.
